UNITED STATES PATENT OFFICE

BEULAH M. ARTHUR, OF LOS ANGELES, CALIFORNIA

DESIGN FOR A BOUQUET

Application filed April 20, 1929. Serial No. 30,953. Term of patent 7 years.

To all whom it may concern:

Be it known that I, BEULAH M. ARTHUR, a citizen of the United States, residing at Los Angeles, in the county of Los Angeles and State of California, have invented a new, original, and ornamental Design for Ornamental Bouquet, reference being had to the accompanying drawing, forming part thereof.

Fig. 1 is a perspective view of the ornament showing my bouquet; and

Fig. 2 is a top plan view of the bouquet shown in Fig. 1.

The invention relates particularly to the use of corrugated or plaited material in irregular arrangement, as shown.

I claim:

The ornamental design for the ornamental bouquet, as shown.

BEULAH M. ARTHUR.
